UNITED STATES PATENT OFFICE.

JOHN BECKER, OF HYDE PARK, MASSACHUSETTS, ASSIGNOR TO BECKER MILLING MACHINE COMPANY, OF PORTLAND, MAINE, A CORPORATION OF MAINE.

UNIVERSAL MILLING-MACHINE.

1,139,475.

Specification of Letters Patent. Patented May 18, 1915.

Application filed February 23, 1909. Serial No. 479,546.

To all whom it may concern:

Be it known that I, JOHN BECKER, a citizen of the United States, and a resident of Hyde Park, in the county of Norfolk and 5 Commonwealth of Massachusetts, have invented an Improvement in Universal Milling-Machines, of which the following description, in connection with the accompanying drawings, is a specification, like 10 letters on the drawings representing like parts.

My invention relates to milling machines and the like and more particularly to feeding means therefor.

15 My invention may be readily understood by reference to the following description of an illustrative embodiment thereof shown in the accompanying drawings wherein,—

Figure 1 is a front elevation of a milling 20 machine embodying my invention; Fig. 2 is a side elevation of Fig. 1; Fig. 3 is an enlarged sectional detail taken on line 3—3 of Fig. 2, looking toward the left; Fig. 4 is a sectional detail taken on the vertical line 25 4—4 of Fig. 3 looking toward the right; Fig. 5 is a sectional detail taken on line 7—7 of Fig. 4 looking toward the right; and Fig. 6 is an enlarged sectional detail on the zig-zag line 8—8 of Fig. 2.

30 In the drawings, referring to Fig. 1 the milling machine illustrating my invention comprises a column-like frame 1 supporting a vertically sliding knee 2 carrying a bed supporting a work table 3, see Fig. 4. Said 35 frame extends upwardly, curving forward to constitute an arm 1^a overhanging the work table 3 to support a vertical spindle 4 having a pulley 5 which is driven in the usual manner from a stepped cone pulley 6 40 by a belt 7, said pulley 6 being mounted on a stud shaft 8 projecting rearwardly from the frame 1 near its base. The belt 7 is guided from said cone pulley 6 to the spindle pulley 5 by pulleys 9 mounted on a 45 short horizontal shaft 10 in a bracket 11 seated on the back of the curved portion of the frame 1. Said shaft and its pulleys may be adjusted to tighten the belt by a screw 12. The speed of the spindle 4 may be varied 50 by the usual back gears 13 (Figs. 1 and 2). The spindle 4 is journaled in a slide block 14 (see Fig. 2) vertically adjustable on the front end of said overhanging arm 1^a by the usual hand wheel 15 having gear connections with said slide not shown herein. A

head 16 (see Figs. 2 and 5) for supporting a horizontal cutter may be attached to the lower spindle bearing 17 on the block 14 by a flange 18 on said bearing registering with a corresponding flange 19 on the upper end 60 of said head. These flanges may be conveniently held together by spaced vertical bolts 20 depending from said flange 18, the heads of which are received by an annular groove 21 in said head flange 19, said groove 65 being T-shaped in section. It will be apparent that by loosening said bolts the head 16 may be turned to adjust the cutter carried thereby to any desired angle in a horizontal plane. This adjustment may be made 70 to an angle of the desired number of degree by reference to a beveled graduated scale 22 (Figs. 1 and 2) on the upper periphery of the lower flange 19 and a mark 23 on the upper adjacent flange 18. The head 16 is 75 provided with a yoke 24 (see Fig. 5) having bosses 25 constituting bearings for a horizontal arbor 26 for receiving a cutter or other tool 27. It will be apparent that by the above described adjustment of the tool 80 supporting head the cutter may be faced in any horizontal direction to give the desired relation between the cutter and work without the necessity of turning the feed table.

Referring more particularly to Fig. 2, about midway in the height of the column 85 is a bracket 62 carrying a change gear mechanism 63 driven at various speeds from a shaft 64 journaled in bearings on said bracket, said shaft having a stepped cone 90 pulley 65 fast thereon driven by a belt not shown herein, from a similar stepped cone pulley 66 mounted on the stud shaft 8 referred to. Power is transmitted to feed the work table from said change gear mechanism by a short shaft 67 having a universal connection with an extensible or telescopic shaft 68 having a similar universal connection with a short shaft 69 (Fig. 4) journaled in bearings in the work table bed 70. Fast 95 on the end of this short shaft 69 is a bevel gear 71 (see Fig. 4) driving in opposite directions the opposed bevel gears 72 and 73 (see Figs. 4 and 5) which are loosely mounted on a transverse shaft 74 journaled in 100 bearings in said bed. The hubs of said bevel gears 72 and 73 are provided with clutch ends of a shifting piece 75 splined to said shaft 74. By sliding this shifting piece to 105 110

the right or the left of Fig. 5 the drive may be transmitted either through the bevel gear 72 or 73, according to the direction of rotation desired. A pinion 76 fast on said bevel gear shaft 74 drives a spur gear 77 having a hub 78 rotative in a bushing 79 fast in the bed 70 referred to. The table feed screw shaft 80 herein is journaled at one of its ends in a bearing in said bed and at its opposite end is supported in the hub of the spur gear 77 (see Fig. 5). This gear constitutes the drive gear for said shaft and may be connected to rotate therewith by a clutch spool 81 splined to said shaft 80, the opposed ends of said gear hub and said spool being provided with clutch faces 81^a, whereby the shaft 80 may be driven automatically through the drive described or be turned manually to adjust it as desired. 10 The screw shaft being mounted in the bed does not travel as in the case where said screw shaft is mounted in the table. Herein the table is fed from the screw shaft 80 by a lug 82 (see Figs. 1 and 4) having a 15 threaded engagement therewith and depending centrally from the work table. Heretofore, so far as I am aware, the rotative feed of the spindle of the index head has been transmitted from a feed screw shaft journaled in the work table and not in the table supporting bed.

I will now describe the mechanism whereby the index head spindle may be given a rotative feed independently of a non-traveling feed screw shaft mounted in the table supporting bed, or whereby said shaft and spindle may be simultaneously operated to give said spindle simultaneously a feed of translation and rotation. To this end (see Fig. 4) the feed screw gear 77, referred to as driving the feed screw shaft 80, also drives a spur gear 91, fast on a short shaft 92 journaled in bearings in said bed, said gear 91 in turn driving a spur gear 93 having a wide hub 94 journaled in a bracket bearing 95 projecting laterally from the rear of said bed 70, said hub being axially retained in said bracket by a collar 96, threaded on the end thereof.

50 As the table 3 is fed on the bed 70 toward the right or left of Fig. 3, the index head 90 will travel with it and in order to give the index head spindle 97 a rotative feed simultaneously with its longitudinal travel to cut helices and spirals, etc., an extensible or telescopic shaft 100 is splined to and mounted to slide longitudinally within a long sleeve 101 which extends through the wide hub of the gear 93 and is splined thereto and rotated thereby. The relative longitudinal movement of said sleeve 101 (see Fig. 3) with respect to said wide hub 94 is limited by stops 102 on the opposite ends of said sleeve one of said stops engaging the shoulder of a counter-bore 103 on the gear

93 and the other engaging the end of the feather 104 which connects said hub and sleeve. The relative longitudinal movement of said sleeve and shaft 100 to the left of Fig. 3 is limited by the engagement of a stop 105 on the inner end of said shaft with the feather 106 connecting said sleeve and shaft and to the right the movement is limited by the engagement of the end of said shaft with a diaphragm 107 fixed into the end of said sleeve.

The telescopic shaft 100 is caused to travel with the index head and table and is moved longitudinally in its sleeve 101 by a lug 108 depending from a frame 109 bolted to the end of the work table (see Fig. 1) and supports a train of gears for transmitting a rotative feed to the index head spindle as more fully hereinafter described. This lug is bored to receive said telescopic shaft and is interposed between collars 110 fixed thereto.

The feeding drive is transmitted from the telescopic shaft 100 to the index head gears by a spur gear 111 (see Fig. 3) fast on said shaft, said gear meshing with and driving a gear 112 directly above it, and loosely mounted on a stud shaft on an adjustable bracket 113 (see Fig. 2) bolted on the frame 109 referred to. Fast upon the hub of the gear 112 is a larger gear 114 which drives a spur gear 115 (see Figs. 3 and 6) directly above it and mounted fast on the outwardly projecting end of a shaft 116 journaled in bearings in said frame 109. When the drive is as just described one speed will be transmitted to said gear 115. A different speed may be transmitted by exchanging the places of the gears 112 and 114 and readjusting said bracket 113. The index head spindle 97 may be given a rotative feed in one direction by a spur gear 117 (see Fig. 6) fast on said shaft 116 meshing with and driving a spur gear 118 fast on an adjacent parallel shaft 119 journaled in bearings in said frame 109. This gear drives a wide faced gear 120 fast on a parallel, adjacent shaft 121, the drive being transmitted therefrom to the index head spindle by the usual gears not shown herein. A wide faced intermediate idler pinion 122 (Fig. 6) fast on a sliding shaft 123, journaled in bearings in said frame 109, is constantly in mesh with said gear 118, and when the drive as described is direct from the gear 117 to the gear 118, this intermediate pinion rotates idly. To give the index head spindle 97 a rotative feed in the opposite direction from that just described the driven gear 118 is slid with its shaft out of mesh with the gear 117; and the former idler pinion 122 with its shaft is moved into mesh with the driving gear 117 and the drive is then transmitted from the gear 117 through the pinion 122 to the gear 118. The sliding shafts 119 and 123 may be retained in their positions of ad-

115

120

125

130

justment by spring pressed latches 124 (see Figs. 1 and 6) engaging peripheral grooves 125 in said shafts. It will be apparent that simply by sliding said shafts 119 and 123 as described, the direction of rotative feed transmitted to the index head spindle may be changed independently of the direction of the work table feed as described.

The rotative feed of the index head spindle may be cut out by simply adjusting the sliding shafts 119 and 123, of the index head transmission to throw any of the gears 117, 118 and 122 out of mesh, the work table and spindle then receiving a movement of translation alone. Also the work table feed may be cut out by unclutching the feed screw shaft 80 (see Fig. 5) from the feed screw gear 77, said gear then serving as an idler to transmit a rotative feed to the index head spindle from the pinion 76 independently of said feed screw shaft. The direction of the rotative feed of said spindle may be changed by clutching the sliding piece 75, (Fig. 5) with one or the other of the bevel gears 72 and 73 or said feed direction may be changed by the sliding shafts 119 and 123 (see Fig. 6) as desired. By my invention the index head spindle 97 on the traveling work table, may be given a rotative feed in opposite directions by a driving mechanism also utilized for driving the non-traveling screw 80 mounted in the table supporting bed 70, the feed being transmitted through the extensible shaft 100 which automatically lengthens and shortens to follow the work table in its travel.

While the transmission means described herein is shown as applied to a rotary index spindle, it will be understood that the spindle is shown for illustrative purposes merely, and that the transmission might readily be applied to a tool different from said spindle or to other movable means carried by the table.

By utilizing the feed screw gear 77 to drive the feed screw shaft and at the same time to constitute the bearing for one end of said shaft and transmit the drive to said telescopic shaft, the number of gears is reduced, the complexity of the machine is lessened and substantially the entire length of the feed screw is available for the travel of the work table feeding lug 82, there being no central gears on said screw shaft for rotating the same and no extra gears thereon for transmitting the rotative feed to the spindle of the index head, as is necessary where the feed screw shaft is mounted in the table and the rotative feed of the index head spindle is transmitted therefrom.

Having described one embodiment of my invention without limiting the invention thereto what I claim as new and desire to secure by Letters Patent is:—

65. A machine of the class described com-

prising, in combination, a spindle; a non-traveling feed screw shaft to transmit a movement of translation to said spindle; and transmission means for imparting a rotative feed to said spindle, said transmission means including means for rotating said shaft.

70. 2. A machine of the class described comprising, in combination, a spindle; a non-traveling feed screw shaft to transmit a movement of translation thereto; and transmission means for imparting rotation to said spindle and shaft having means detachably to connect said transmission means with said shaft whereby to rotate said spindle independently of said shaft.

75. 3. The combination of a table and movable means carried thereby, with driving means therefor, including a table feed screw connecting means from the latter to said movable means, and a clutch for detachably connecting said connecting means with said screw, whereby said table and movable means may both be operated simultaneously, or the latter may be operated without operating the table.

80. 4. The combination of a work table and a rotative instrumentality carried thereby having provision for acting on the work, and transmission means for said table and said instrumentality having provision for operating both said instrumentality and table simultaneously, or for operating said instrumentality without operating said table.

85. 5. The combination of a work table and a rotative instrumentality carried thereby having provision for acting on the work, driving means and transmission means extending from said driving means to said table and said instrumentality and including clutch means whereby said instrumentality and table may be operated simultaneously, or said instrumentality may be operated without operating said table.

90. 6. A machine of the class described comprising, in combination, a table; a spindle mounted thereon; a non-traveling feed screw shaft to transmit a movement of translation to said table; and transmission means for imparting a rotative feed to said spindle independently of said shaft.

95. 7. A machine of the class described comprising, in combination, a table; its bed; movable means mounted on said table; driving means on said bed; and extensible means extending from said bed to said table for transmitting a feed to said movable means irrespective of relative movements between said table and its bed.

100. 8. A machine of the class described comprising, in combination, a table; its bed; means movably mounted on said table; driving means on said bed and a telescopic shaft extending from said bed to said table for

transmitting a feed to said movable means irrespective of relative movements between said table and its bed.

9. A machine of the class described comprising, in combination, a table supporting bed, a work table adapted to be fed relatively thereto, an index head spindle on said table, driving means on said bed and transmission means coöperating with said driving means and spindle and including extensible means to feed said spindle from said driving means.

10. A machine of the class described comprising, in combination, a table; a supporting bed therefor; a spindle carried by said table; a feed screw shaft journaled in said bed for feeding said spindle longitudinally; driving means on said bed; and an extensible shaft extending from said bed to said table to transmit a rotative feed from said driving means to said spindle irrespective of relative movements between said bed and table.

11. A machine of the class described comprising, in combination, a table, a non-traveling feed screw shaft for imparting a movement of translation to said table; a screw shaft driving gear on said shaft constituting a bearing for said shaft and means detachably to connect said gear to said shaft.

12. A machine of the class described comprising, in combination, a bed, a work table thereon, a table feed screw shaft journaled in said bed, a spindle on said table, a gear having a wide hub journaled in said bed and constituting a bearing for one end of said shaft and adjustable means detachably to connect said gear to said shaft to drive the latter from said gear.

13. A machine of the class described comprising, in combination, movable means; a support therefor; and transmission means for imparting movements of translation and rotation to said movable means including a non-traveling feed screw shaft journaled in said support; and means for varying the direction of the rotative feed of said movable means independently of the direction of rotation of said shaft.

14. A machine of the class described comprising, in combination, a table; its bed; a spindle mounted on said table; driving means on said bed; and means for transmitting a feed to said spindle, irrespective of relative movements between said table and bed, including a plurality of gears carried by said table for transmitting the feed to said spindle and axially adjustable gears interposed between said gears for varying the direction of feed of said spindle.

15. A machine of the class described comprising, in combination, a table; its bed; a spindle mounted on said table; driving means on said bed; and means for transmit-

ting a feed to said spindle, irrespective of relative movements between said table and bed, including a plurality of gears carried by said table for transmitting the feed to said spindle, axially adjustable shafts and gears fast thereon interposed between said first named gears to vary the direction of said feed; and means to retain said shafts in their positions of axial adjustment.

16. A machine of the class described comprising, in combination, a bed; a table thereon; rotative means mounted on said table; and transmission means for imparting a rotative feed to said rotative means irrespective of relative movements between said table and bed; and means mounted on said table for changing the direction of rotative feed of said rotative means.

17. A machine of the class described comprising, in combination, an index head spindle; a support therefor; and transmission means for imparting movements of translation and rotation to said spindle including a non-traveling feed screw shaft journaled in said support.

18. A machine of the class described comprising, in combination, a bed; a work table thereon; means for feeding said table along said bed; rotative means carried by said table; and driving means on said bed having provision for rotating said rotative means independently of said table feeding means.

19. A machine of the class described comprising, in combination, a bed; a table adapted to be fed thereon; a spindle carried by said table; a non-traveling feed screw shaft journaled in said bed; means on said table for threaded connection with said screw shaft whereby rotation of the latter may feed said table; and driving means for transmitting a feed to said spindle, said driving means including means for rotating said shaft.

20. A machine of the class described comprising, in combination, a bed; a table thereon; a non-traveling feed screw shaft journaled on said bed for feeding said table; a spindle carried by the latter; and means to transmit a rotative feed to said spindle without rotation of said screw shaft.

21. A machine of the class described comprising, in combination, a support; a work table thereon; means for feeding said table relatively to said support; rotative means mounted on said table and having provision for acting on the work; driving means on said support and transmission means extending from said driving means to said table for transmitting power to said rotative means independently of said table feeding means.

22. A machine of the class described comprising, in combination, a support; a table thereon; means for feeding said table relatively to said support; movable means

mounted on said table; driving means on said support; and means for transmitting power to said movable means from said driving means including a shaft movable in 5 the direction of its axis with said table and means to rotate said shaft from said driving means while permitting the axial movement of said shaft.

23. A machine of the class described comprising, in combination, a support; a work table thereon; means for feeding said table relatively to said support; a rotative instrumentality mounted on said table and having provision for acting on the work; driving means on said support; and means extending from said driving means to said instrumentality for transmitting power to the latter including a shaft rotated by said driving means irrespective of relative movement between said table and support.

24. A machine of the class described comprising, in combination, a support; a work table adapted to be fed relatively thereto; a rotative instrumentality on said table and

having provision for acting on the work; 25 driving means on said support; and means to transmit power from said driving means to said instrumentality including a shaft and gear, and means permitting relative movement between said shaft and gear on 30 movement of said table relatively to said support.

25. A machine of the class described comprising, in combination, a support; a work table thereon; means for feeding said table 35 relatively to said support; rotative means mounted on said table and having provision for acting on the work; and means for automatically operating said rotative means independently of said table feeding means. 40

In testimony whereof, I have signed my name to this specification, in the presence of two subscribing witnesses.

JOHN BECKER.
